COMBINATION MOP HEAD HOLDER AND BRUSH HOLDER

Eva Dryden, 6137 Morella Ave., North Hollywood, Calif.
Filed Feb. 18, 1963, Ser. No. 259,049
2 Claims. (Cl. 15—115)

Generally speaking, the present invention relates to a combination mop head holder and brush holder means including a base means adapted to be effectively provided with handle means, spaced clamping bar means, and means for effectively clamping said clamping bar means with respect to said base means with a portion of a mop head (usually a central portion of a multiple strand mop head means, although not specifically so limited) therebetween whereby to lock said mop head in operative relationship with respect to said base means and with respect to said handle means in a manner such as to comprise a complete mop adapted for any suitable type of mopping action.

The novel base means of the present invention comprises both a laterally elongated base member and an integrally connected, laterally elongated, substantially horizontal and rearwardly directed planar brush holder means taking the form of a brush holder panel member, with both said base member and said brush holder panel member being formed out of one piece of thin-sheet material so as to minimize construction problems and cost as compared to prior art devices intended for generally similar purposes.

The novel brush holder panel means of the present invention is adapted to be effectively provided with a scrubbing brush means which is of a type including a back portion and a plurality of substantially downwardly directed bristles extending from a lower surface of said back portion and, therefore, also extending effectively downwardly with respect to said base member of the mop head holder and positioned closely adjacent thereto and usually a little bit behind said base member of said mop head holder whereby to be located in a manner adapted to act as a back-up member for the mop head and whereby to also be adapted to be placed in direct scrubbing contact with any underlying surface, such as a floor surface or the like, for scrubbing difficult-to-clean portions of said underlying surface which could not otherwise be effectively cleaned by the conventional mop head means.

In one exemplary form of the invention the brush holder means comprises a brush attachment panel member effectively integrally connected with respect to said base member of the mop head holder. This is so by reason of the provision of integral connection means integrally connecting said brush attachment member with respect to said base member of said mop head holder.

In one preferred form of the invention said integral connection means is carried adjacent to the forward edge of said brush attachment member and effectively integrally connects same with respect to a lower edge portion of said base member whereby to integrally mount said brush attachment member in a lower, rearwardly directed relationship with respect to said base member of said mop head holder in a manner such that a downwardly directed scrubbing brush mounted underneath said rearwardly directed brush attachment member will be positioned behind and will effectively extend downwardly below the level of said base member of said mop head holder whereby to be ideally located for effective back-up supporting cooperation with a mop head during a floor mopping operation and/or for independent direct scrubbing contact with a floor surface during a floor scrubbing operation.

It is a further object of the present invention to pro-

2

vide a device of the character referred to hereinbefore which is of relatively simple, inexpensive, easy-to-install, easy-to-use construction and which greatly extends and expands the usefulness and effectiveness of a conventional mop head holder, whereby to be conducive to widespread usage of the device.

For the purpose of clarifying the nature of the present invention, an embodiment is illustrated in the hereinbelow described figures of the accompanying drawings.

FIG. 1 is a fragmentary, reduced-size, side elevational view of one exemplary embodiment of the invention wherein the brush holder means is integrally connected with respect to the base member of the mop head holder, said brush holder means and said integrally connected base member together effectively comprising a complete base means which, when further provided with the clamping means shown in FIG. 1, comprises said mop head holder. In this view the apparatus is so oriented as to facilitate a floor mopping operation by employing the brush holder means of the present invention and a brush carried thereby for effective back-up or pressure-applying purposes with respect to the multiple strand mop head lying between said brush and an underlying floor surface which is to be mopped.

FIG. 2 is a smaller size, fragmentary, side elevational view generally similar to FIG. 1 but illustrating the apparatus so oriented with respect to an underlying floor as to facilitate a direct floor scrubbing operation rather than a floor mopping operation of the type illustrated in FIG. 1.

FIG. 3 is a fragmentary, top plan view of the apparatus illustrated in FIG. 1.

FIG. 3A is an enlarged fragmentary side elevational view of the transverse base means of the mop head holder of FIG. 3 with all other parts removed.

FIG. 4 is an enlarged fragmentary view, partly in section, taken along the plane represented by the line 4—4 of FIG. 3.

FIG. 5 is a top plan view of the base means of the apparatus of FIG. 3 but with the mop head, mop head clamping bar means, mop handle, and brush all removed for reasons of drawing simplification and clarity.

Generally speaking, the brush holder means for a mop head holder of the present invention comprises the brush holder means, indicated generally at 21, which carries brush-engageable attachment means, indicated generally at 22, for attachment with respect to a scrubbing brush, such as indicated generally at 23 whereby to firmly mount the scrubbing brush 23 in a position suitable for surface-scrubbing or floor-scrubbing operation thereof, as will be described in greater detail hereinafter.

In the exemplary form of the invention described and illustrated, the brush attachment means 21 takes the form of a substantially flat, horizontal brush attachment panel member 24, and the brush-engageable attachment means, indicated generally at 22, takes the form of a plurality of apertures 25 adapted to carry fastening members, such as the fastening screws 26, or the like, for controllable attachment to the back portion 27 of the scrubbing brush means 23 whereby to firmly mount the scrubbing brush 23 underneath the flat brush attachment panel member 24 with the plurality of bristles 28 downwardly directed into a position adapted for effective floor scrubbing action or mop head back-up and supporting action as will be described in greater detail hereinafter.

The brush attachment means, indicated generally at 21, is adapted to be connected with respect to a mop head holder, one exemplary type of which is indicated generally by the reference numeral 29. This connection is adapted to be provided by effective connection means, one exemplary form of which is generally designated

by the reference numeral 31 in said exemplary form of the invention referred to above as best shown in FIG. 4.

In said exemplary form of the invention referred to above, the mop head holder 29 comprises a base means generally designated at 30 and the clamping bar means generally designated at 37, which will be referred to in detail hereinafter. It should be noted that the base means generally indicated at 30 itself comprises the brush attachment means indicated generally at 21, and taking the form of the brush holder panel 24, and also comprises the transversely directed base member 32, said base means indicated generally at 30 also being provided with upwardly and rearwardly directed handle attachment means 33 which is shown as taking the form of a bifurcated split socket 34 adapted to receive and to be firmly fastened with respect to the forward end 35 of a longitudinal handle 36.

The mop head holder 29 also includes a transversely directed clamping bar means 37 which, when opened, is spaced from the similarly transversely directed base member 32 and is positioned forwardly therefrom in a substantially parallel relationship with respect thereto. The clamping bar means 37 is provided with a pair of connection members 38 connected to each end thereof and extending upwardly and rearwardly to pivotal connection portion 39 of a controllably operable, over-center, spring-biased lever actuating means which is adapted to be operated between two extreme positions for positioning the clamping bar means 37 in either the above-mentioned open spaced relationship with respect to the transversely directed base member 32 or in closely adjacent abutting clamping relationship with respect thereto.

One exemplary and non-specifically limiting form of said controllably operable over-center lever actuating means is indicated generally at 41 and comprises the sliding forward portion 41 slidably carried on the longitudinal handle 36 and in abutting relationship with respect to the compression spring 43 which is also mounted on the longitudinal handle 36 between the forward portion 42 (to which it is pivotally connected as indicated at 44) and the handle attachment socket 34 carried by the transversely directed base member 32, to which it is connected by the retaining lip 45.

The arrangement is such that the compression spring 43 applies a force against the forward portion 42 tending to force it away from the base member 32.

The over-center means 41 also includes an operating lever portion 46 spaced from the pivot point 44, thus providing an arrangement such that operation of the operating lever 46 into an outwardly projecting position with respect to the longitudinal handle 36 will allow the abutting forward portion 42 to move away from the socket 34 and will simultaneously allow the pivotal connection portions 39 and the connection members 38 attached to the clamping bar means 37 to move forwardly in a manner such as to move the clamping bar means 37 into open or spaced relationship with respect to the transversely directed base member 32.

On the other hand, movement of the lever handle 46 into a position parallel to the longitudinal handle 36 and in substantial side abutment therewith causes the reverse action—that is, causes tension to be applied to the connection portions 39 of the over-center actuating means 41 whereby to apply tension to the connection members 38 in a manner such as to pull the clamping bar means 37 toward the transversely directed base member 32 whereby to clamp therebetween the central portion, indicated generally at 47, of a mop head, indicated generally at 48.

It should be noted that the transversely directed base member 32 is provided with an upper flange portion 49, a central recessed portion 51 toward which the clamping bar means 37 is adapted to be drawn when the device is locked by operation of the over-center actuating means

41, and a rearwardly extended lower flange which effectively comprises the hereinbefore mentioned brush attachment means, as indicated generally at 21 and referred to in the specific exemplary form of the invention as comprising the hereinbefore mentioned brush attachment flat horizontal panel member 24.

The hereinbefore mentioned connection means, indicated generally at 31, comprises the integral, rigid, angular junction edge 52 formed by the lower edge of the base member, indicated generally at 32, and the forward edge of the brush attachment panel member 24.

This provides an integral arrangement which mounts the scrubbing brush means 23 below and slightly behind the base member 32 of the mop head holder 29 so that the bristles 28 of the scrubbing brush means 23 may be used for effective back-up supporting cooperation with the mop head 48 when it is applied to a floor surface, as indicated at 53, whereby to increase the efficiency of a floor mopping operation. This is clearly shown in FIGS. 1 and 3.

Also, the scrubbing brush means 23 may be moved so as to have its bristles 28 in direct scrubbing contact with the underlying floor surface 53 for greatly increased floor cleaning effectiveness by reason of the direct scrubbing action produced in this manner and which cannot be accomplished by a conventional mop head. This is clearly shown in FIG. 2.

It should be clearly noted that the complete base means, indicated generally at 30 (as best shown in FIG. 3A) and including the transversely elongated base member 32 and the brush holder panel member 24, comprises an integral plate of thin-sheet material integrally formed into the angular relationship most clearly shown in FIG. 3A and with said integral connection means 31 interconnecting same, thus making it possible to manufacture the complete base means 30 at extremely low cost. This makes it possible to produce and sell the entire device at a substantially lower cost than any prior art apparatus or device intended for substantially similar purposes and thus greatly extends the general usefulness of the invention.

I claim:

1. A combination mop head holder and brush holder means comprising: a base means having a forward direction and an opposite rearward direction and two oppositely aligned transverse directions substantially perpendicular to said forward and rearward directions, said base means being transversely elongated and being integrally provided with upwardly and rearwardly directed handle attachment means comprising bifurcated split socket means positioned for fastening attachment with respect to a corresponding mating forward end portion of a longitudinal operating handle means, said base means comprising a laterally elongated base member provided with clamping bar means positioned forward of said laterally elongated base member and being similarly laterally elongated and being relatively movably mounted with respect to the corresponding rearwardly adjacent laterally elongated base member for controllably clamping or releasing a mop head between said laterally elongated clamping bar means and said laterally elongated base member; and controllably operable actuating means effectively coupled between said laterally elongated clamping bar means and said laterally elongated base member for relatively forwardly and rearwardly moving same between a separated non-clamping relationship and a closing clamping relationship; said transversely elongated base means further comprising an integral brush holder means taking the form of a substantially flat horizontally transversely elongated and rearwardly directed brush holder panel member integral with said transversely elongated base member and forming therewith a rigid integral connection means at the forward edge of said brush holder panel member and at the lower edge of said transversely elongated base member in an angular relationship such as to include an acute angle between

said upwardly and rearwardly directed socket means and said brush holder panel member, said base means comprising said transversely elongated base member and said transversely elongated rearwardly extending brush holder panel member comprising an integral plate of thin-sheet material integrally formed in said angular relationship with said rigid integral connection means therebetween; said brush holder panel member being provided with brush-engageable attachment means comprising threaded fastener means carried by said brush holder panel member and projecting vertically downwardly therefrom for controllably disengageable threaded fastening attachment with respect to the back of an auxiliary scrubbing brush means having a plurality of downwardly directed bristles extending from the lower surface thereof in a position for effective back-up supporting cooperating with a mop head during a floor mopping operation and for direct contact with an underlying horizontal floor surface during a floor scrubbing operation.

2. A device as defined in claim 1, wherein said controllably operable actuating means is effectively connected with respect to said transversely elongated clamping bar means and comprises a controllably operable over-center, spring-biased, lever-type actuating means positioned for operation between two extreme over-center positions, in one of which it positions said clamping bar means in said separated non-clamping relationship and in

the other of which it positions said clamping bar means in said closed clamping relationship with respect to said laterally elongated base member and maintains it in said relationship until controllably released therefrom, said lever-type actuating means including compression biasing spring means effectively positioned between a controllably movable abutment portion of said lever-type actuating means and the rear upper end of said socket means whereby to normally bias said lever-type actuating means into a mop head releasing position wherein it positions said clamping bar means in said separated non-clamping relationship with respect to said base member.
